DIAMOND GRINDING WHEEL
CONSTRUCTION

Gunnar E. Hollstrom, Worcester, Mass., assignor
to Norton Company, Worcester, Mass., a corpora-
tion of Massachusetts

Application August 6, 1945, Serial No. 609,202

2 Claims. (Cl. 51—209)

1

This invention relates to grinding wheel or grinding disk construction, and more particularly to grinding disks for surface grinding—usually flat surfaces of various materials, such as glass.

One of the objects of this invention is to provide a practical and efficient grinding disk construction that will be of relatively inexpensive, yet strong and durable, construction and well adapted for efficient use of costly abrasives, such as diamond grains, diamond dust, and the like. Another object is to provide a built-up abrasive structure of the above-mentioned character in which the individual parts will be capable of efficient and inexpensive manufacture and rapid and dependable assembly. Another object is to provide an abrasive structure of the just-mentioned character in which diamond or like abrasive-bearing elements can be reliably mounted in position to effectively withstand the thrusts and stresses of grinding reaction. Another object is to carry out the last-mentioned object in a manner to achieve ease and speed of replacement of such elements without impairment of reliability and efficiency of support or mounting. Another object is to provide a multiple or built-up structure of the above-mentioned character with means to expedite replacement of elements of the just-mentioned character. Another object is, in general, to provide an improved disk type of abrasive structure, particularly for the grinding of surfaces of large areas, usually flat, and other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings, in which are shown several of the various possible embodiments of my invention—

Fig. 1 is a plan view of a ring or disk type of abrasive structure made according to my invention;

Fig. 2 is a transverse sectional view, on an enlarged scale, as seen along the line A—A of Fig. 1, showing one form of construction;

Fig. 3 is a view like that of Fig. 2, showing another form of construction, and

Fig. 4 is a view like that of Fig. 2, showing another form of construction, certain parts being shown in elevation, while

Fig. 5 shows the structure of Fig. 4 as it is preferred to carry it out according to the character

of certain of the materials that may be employed.

Similar reference characters refer to similar parts throughout the several views of the drawings.

5 Referring first to Fig. 1, I have there shown a disk-like or annular support, generally indicated by the reference character 10, preferably provided with an internal or central opening 11 for a purpose later described and projecting from its 10 front face 12 which, illustratively, is flat or plane, is a suitable number of suitably distributed individual or separate and preferably composite or built-up elements, generally indicated by the reference character E, each constructed to have a 15 cantilever portion and to present at the outer end of the cantilever part an abrasive face 15a of any suitable shape or configuration, illustratively circular. The cantilever abrasive-carrying elements E project beyond the face 12 of the annular support 10 and where the grinding operation is to be performed upon a flat surface such as plate glass, for example, the faces 15a fall in the same flat plane though it is to be understood that, according to the particular grinding operation to be performed or the shape of the surface of the work-piece to be ground, the abrasive faces 15a can be shaped to define or fall within any other suitable surface of revolution.

Any suitable and preferably uniform distribution of the elements E throughout the face 12 of the support 10 may be used and in the drawing I have shown a uniform distribution achieved by positioning the elements E at equal distances from the axis of the support 10 and giving them 30 equal spacings, center to center, along the geometric circle on which their centers thus lie.

The annular support 10 is adapted to be mounted in any suitable way for rotation at suitable speed—illustratively, about a vertical axis—40 with the elements E on the underside of the support 10, and any suitable means (not shown) may be employed for so mounting and driving the support 10; usually such means are constructed to be provided with a suitable passage or passages, 45 usually coaxial, for guiding a suitable liquid coolant to the area of the work-piece that falls within the effective abrasive annulus as the abrasive structure is pressed against the surface of the work-piece being ground, whence it moves or flows radially outwardly to be brought into the 50 region of grinding contact with the workpiece. In Fig. 1 I have indicated at 13 a number of suitably distributed, threaded holes opening from the underside of the support 10, as viewed in Fig. 1, 55 and being of suitable depth, whereby, with the

use of screws, the annular support 10 is secured to any suitable driving carrier such as the kind just described. These holes 13 need not emerge at the face 12 of the support 10, and they can be proportioned or located so as not to interfere with the location, mounting, or construction of the elements E.

For convenience of illustration, as well as convenience of manufacture of the construction, the elements E are preferably of circular cross-section—particularly as to the mounting portion thereof, as later described—though it will be understood that my invention is not thereby to be so limited excepting as it may be so limited in one or more of the claims. Each element E preferably comprises an abrasive portion 15 and a mounting portion 16, and preferably and conveniently these two portions are of the same cross-section, illustratively circular, and they may be initially formed as a single entity or unit, or they may be separately constructed and then integrally joined or united. In axial length, that is, in their dimension parallel to the axis of the annular support 10, the mounting portions 16 of the elements E are preferably of substantial length for coaction with the annular support 10, in a manner later described, and they are constructed to have good resistance against strain in a direction transversely of their length; a circular cross-section is illustrated in the drawings and is good for this purpose. Referring to Fig. 2, the support 10 is preferably of substantial vertical or axial dimension and, opening into the annular face 12 thereof, it is provided, in any suitable way, with receiving chambers C, one for each element E, each preferably of substantial depth or axial dimension. The mounting portion 16 of the element E and the chamber C are of similar cross-section, illustratively circular, and the two parts are proportioned so that the one is receivable into the other with the desired fit which may be tight or snug or may have some tolerance according to circumstances later described.

In the form shown in Fig. 2, the mounting portion 16 of element E is a straight cylinder as is also the wall 17 of the chamber C, and preferably the end face 18 of the element E extends at right angles to the axis of the element, in which case also it is preferred that the bottom wall 19 of the chamber C extend likewise at right angles to its axis so that the face 18 and the wall 19 can be parallel to each other.

Preferably coaxially of each chamber C, I provide a hole 21 in the annular support 10, which hole is threaded, as shown, being preferably of a diameter relatively large as compared to the diameter of the chamber C, and hence, where the hole 21 is employed, the bottom wall of the chamber C is annular. I close off this hole 21 by a pressure-applicator which tightly fits the hole and where the hole is threaded, as in the illustration, it is preferably in the form of a screw 22, the end face 23 of which is preferably squared off relative to the axis of the screw so that with the annular wall 19 it can form a complete bottom wall for the chamber C. The screw 22 is provided with any suitable means to facilitate turning it, and conveniently this takes the form of a head 24, which may be hexagonal. Preferably also the cross-section of the annular support 10 is so proportioned and dimensioned that, with the end face 23 of the screw 22 in alignment with the bottom wall 19 of the chamber C, the head 24 falls within the annular end

face 25 of the support 10, being accommodated in a counterbore 27 which is of such a depth as to permit the end of the screw, when it is turned, to partake of substantial movement into the chamber C, the counterbore 27 being of sufficiently large width to accommodate a socket wrench or the like when applied to the screw head 24 to turn it. Any suitable pitch of thread may be employed, and preferably a thread of relatively small pitch, so that, upon turning of the screw 22, its axial movement is relatively small per unit of angle of turn so that substantial multiplication of force may be achieved, for purposes later described. With the screw 22—24 normally accommodated within the plane of the face 28 of the annular support 10, the latter may be secured to the rotating or driving carrier above described without interference by or from the screw head 24, and in Fig. 2 I have indicated, in broken lines at 29, such a driving carrier against a face of which the face 25 of the annular support 10 rests and is clamped, as by the above-mentioned screws coacting with the holes 13 in the support 10, thus also closing over the counterbores 27.

The annular support 10 may be constructed of any suitable material and in any suitable manner. It may be of metal throughout, machined or conformed to shape in any suitable way. For example, the counterbore 27, rather than being individual to each screw, is preferably an annular recess to give the base of the support 10 the cross-section of an inverted U, and may be readily turned as on a lathe, the holes 21 may be drilled and thereafter threaded, and, where the chambers C are to be of circular cross-section, they may be formed in a similar manner. Or the annular support 10 may be formed of any other suitable material, such as moldable and usually heat-curable material, usually resinous in character, and including any suitable fillers or other ingredients or materials to give it the desired characteristics. In such case the annular support 10 may be molded in a suitable mold, by known techniques, usually employing pressure and heat during the molding, or heating for curing or setting subsequent to molding under pressure. Illustratively I may employ any of the known heat-curable resins, such as phenol formaldehyde, with which may be mixed powdered metal, illustratively aluminum, in proportions, illustratively, on the order of from 5% to 25% by volume of the resin, the latter and the metal, both in powdered form, being thoroughly intermixed and thereafter molded and heat-treated. In such case the holes 21 are molded straight and are threaded after cure. In any case the support 10 is made of a material that will give the desired rigidity of support to the cantilever portions of the elements E; its U-shaped cross-section can advantageously coat in this respect.

The elements E preferably have an abrasive portion 15 and a mounting portion 16, as above described, the abrasive portion 15 preferably having diamond grain or powder as the abrasive ingredient—in which case the axial dimension or thickness of the abrasive portion 15, as viewed in Fig. 2, may be relatively small—on the order of $\frac{1}{8}$ " to $\frac{1}{4}$ ", or the like—bonded by any suitable bonding material, and preferably a material that is the same as is used, according to my invention, in making the mounting portion 16. For example, I may use any material known in the art as "resinoid"—and of which phenol formaldehyde

resin is an illustration—as a bond for the diamond grain in making up the abrasive portion 15 and as the material, with or without suitable fillers, of which to make the mounting portion 16. For example, for the latter I may include powdered metal—illustratively, in the proportions above mentioned—and, depending upon grinding characteristics desired for the abrasive portion 15, I may also include in the latter any suitable metal in powdered form. The portions 15 and 16 may have their respective ingredients first suitably mixed in two respective mixes and then suitable quantities of these two mixes successively placed in a suitable mold, which is preferably shaped to give the abrasive portion a rounded-over annular portion R of suitable radius, somewhat as indicated in the drawings, for a purpose later described. The two mixes in the mold are then subjected to suitable pressure and, if desired, one mix, such as that of the abrasive portion 15, may first be injected into the mold and subjected to pressure, and thereafter the mix representing the mounting portion 16 superimposed and again pressure applied, whence curing, as by heat, takes place. The two portions are thus strongly united along a plane of demarkation, indicated at P, and the junction at P in this preferred manner is given a character such that shear in the direction of the plane of the junction, under the stresses of grinding, is adequately withstood.

Instead of employing a resinoid material which includes rubber, both natural and synthetic, I may employ other materials, such as vitrifiable mixes or bonds, molding or forming them and firing them in known manner. The portions 15 and 16, in such case, are preferably assembled or molded as a unit, so that the vitrifiable bond materials of the two portions unite along the plane at the junction P to form an integral abrasive element E. Or I may form or make the portions 15 and 16 of the abrasive element E separately of any suitable materials or combinations of materials, and unite the abrasive portion 15 and the mounting portion 16 along the plane P by the use of any suitable cementing or joining material, such as resin cements which are self-curing or self-setting, or resin cements that can be set or cured under suitable heat treatment. For example, a phenol formaldehyde type of cement can be employed in liquid or semi-liquid form at the junction along the plane P and then heat-treated to set it. In this manner the mounting portion may be made of any material more suitable for coaction with the chamber C, into which it is to be received, depending usually upon the material employed in making the annular support 10. For example, the latter may be of solid metal throughout and so, also, the mounting portion 16 to which the wafer-like abrasive portion 15 is integrally united in a manner such as that just described. Such an arrangement makes it possible to match the thermal coefficients of expansion of the mounting portion 16 and the annular support 10, and permits the economical application of abrasive portions or wafers 15 according to whatever bonding material for the diamond grain is most suitable or desirable for the particular grinding task. Where the mounting portion is molded, with or without the abrasive portion 15, the mounting portion 16 may be, with facility, given the desired dimensions for coaction with the chamber C—though, if desired, these parts may be molded somewhat oversize and then turned or ground down to the desired dimension for coaction with the chamber C.

In one form of my invention the mounting portion 16 of the abrasive element E is dimensioned to be received in the chamber C with a very slight clearance between the side walls to accommodate therebetween a suitable cement or settable adhesive—for example, a cement of the kind described above in case the abrasive portion 15 and the mounting portion 16 are cemented together—and a clearance on the order of one or two thousandths of an inch or so, varying with the cross-sectional dimensions of the part 16 and the chamber C, may suffice. In seating the mounting portion 16 in the chamber C, the adhesive or cementing material, in suitable liquid or semi-liquid form, is applied to the side and bottom walls of the chamber C and to the side and bottom faces of the mounting portion 16, and the latter then forced or pressed into the chamber C. This is preferably carried on with the screw 22 removed, particularly in cases where it is desired to maintain minimum possible clearance, the hole 28 thus preventing entrapment of air and the creation of possible voids in the layer or film of cement, as might be the case if the chamber C were closed at its bottom so that the entry of the mounting portion 16 would have a piston action; such piston action, in compressing the air ahead of the part 16 as it enters the chamber C, can have the effect of blowing more or less of the cementing material out through the side clearance as the air seeks escape. With my invention, however, a dependable and uniformly distributed layer of the cementing material of the desired thickness may be dependably achieved, it being noted that the chamber C is of substantial depth to receive a substantial length of the mounting portion 16 to give the latter good lateral or transverse mechanical support against the reaction from the grinding stresses. That reaction is one of transverse shear as viewed in Fig. 2, tending to bend the mounting portion 16, and it increases with increase in the pressure of the rotating grinding unit (upwardly in Fig. 2) against the surface of the work being ground which is engaged by the upper end face 15a of the abrasive portion 15; as against such stresses, the relationship between the chambers C and mounting portions 16 gives good rigidity of support against displacement and also dependable cantilever anchorage for the mounting portions 16 so that they cannot tilt or vibrate or chatter. With uniformly-dimensioned abrasive elements E, the arrangement above described also facilitates the uniform bottoming of all of the composite elements E against the bottom walls 10 of the chambers C, thus bringing all of the abrasive faces 15a of the abrasive wafers substantially into the same plane and thus lessening the extent, if any, to which these end faces 15a need to be subsequently ground off or trued to place them in the desired common plane.

The cement may now be allowed to set, or the structure may be heat-treated where the cement requires heat to cure it, whereupon the screw 22, preferably with cement applied to its end face 23, may now be entered into the threaded hole 24 to a position substantially like that shown in Fig. 2, thus closing off the hole 24 and interposing a layer of film of settable or curable cement between its end face 23 and the central portion of the end face 15 of the mounting portion 16; or the screw 22 may be so entered into position before the cement that joins the mounting portion 16 of the walls of the chamber C is set, particularly if heat treatment is required, so

that subsequent heat treatment effects setting of that cement, as well as the cement at the end face 23 of the screw 22.

The driving or supporting carrier 28 may now have the grinding structure applied to it and the end faces 15^a may be trued, if needed, it being noted that a minimum loss, if any, of expensive abrasive, such as diamond grain, is incurred due to the features of achieving nicety of alignment above described. In operation the rounded-over portions R of the abrasive portions 15 form, with the surface being ground, an appropriate angle to facilitate entry into the grinding contact between the work and the abrasive portions of liquid coolants or grinding-promoting liquids, and the number and distribution of the abrasive elements E facilitate bringing to these angles of the liquid or liquids desired, the spacings between the elements permitting free flow of the liquids between the abrasive portions 15, as earlier above indicated. Substantial pressures, as may be needed, may be exerted between the rotating grinding structure and work, and the side or lateral thrusts are well resisted, in shear, by the projecting part of the mounting portion 16 and transmitted and taken up by the annular support 10 without tilting of the mounting portion 16 relative to the axis of the annular support 10.

When the diamond-bearing abrasive portion 15 of each of the composite elements E is worn down to the plane of junction P, the annular support 10 is detached from the carrier 28 for replacement of the worn elements E. This is achieved by applying a socket wrench to the head 24 of the screw 23 and turning the screw, with appropriate leverage, to thread or move it upwardly as viewed in Fig. 2. The torque thus applied to turn the end face 23 of the screw 22 breaks, as by shear, the cement uniting the end face of the mounting portion 16 to the screw and through the upward movement of the screw 22, there is applied to the element E a force which is a very substantial multiplication of the force applied to the socket wrench to dislodge the element E from its chamber C and, where cement is employed as above described, to break the union or junction effected by the cement. In the illustrative embodiment in Fig. 2, the bond of the cement between the side face of the mounting portion 16 and the side wall 17 of the chamber C is broken as is also the junction between the annular bottom wall 19 and the contiguous portion of the bottom face 23 of the element E. By using a thread of small pitch, the force exerted by the screw 22 to dislodge the inserted member can be made of appropriate magnitude. The elements E may thus be quickly removed. The walls of the chambers C are suitably cleaned off of any remnants of cement adhering thereto, whence new elements E may be assembled to the structure in the manner above described. Furthermore, I may secure the cantilever mounting portion 16 in its chamber C by the frictional grip of the side walls of the latter upon the side surfaces of the former, and such an anchorage may be effected by a pressure or force fit of the one part in the other; such an anchorage is best effected where both parts are metallic, but I do not mean thereby so to limit my invention. With such an anchorage replacement of elements E is easily effected in the manner above described by the use of the screw 22.

In Fig. 3 suitable lengths of the mounting portion 16 of the abrasive element E and of the side

wall 17 of the chamber C are threaded, preferably throughout the entire length of the chamber C, and this arrangement is particularly feasible where the securing portions 16 of the elements E are made round in cross-section. In such case I preferably again employ a hole 21, and in the end face 18 of the mounting portion 16 I make suitable provision for engaging it with a suitable tool so that the element E may be turned for engaging or disengaging the threaded portions of the parts 16 and C for assembly or disassembly. Thus I may form a suitable tool-receiving recess or socket such as a diametrically extending slot 18^a in the lower end of the mounting portion 16 to receive a suitably heavy screwdriver or the like, which can be turned with any suitable known lever arrangement, the tool being interengageable with the lower end of the mounting portion 16 by way of the hole 21. Preferably the hole 21 is threaded as shown in Fig. 2 to receive screw 22; after the element E is tightly threaded into the chamber C, preferably so that a suitable shoulder or face such as its underface 18 bottoms against the annular shoulder or wall 19 of the chamber C, the screw 22 may be turned up to bring its underface 23 flatwise into engagement with the underface 18 of the element E and serve as a jamming or locking screw to resist loosening up or turning of the abrasive element E, particularly under the vibration or stress of grinding.

The screw 22 may be provided with a head 24 which, as in Fig. 2, may be accommodated in a counterbore 27 of the annular support 10. If desired, a suitable cement—such as any of those set forth above—may be employed to coat between the mounting portion 16 and the chamber C and between the mounting portion 16 and the end face 23 of the screw 22. For example, cement may be applied between the end face 18 of the element E and the annular bottom wall 19 of the chamber C and the end face 23 of the screw 22, and, when set, aids in holding the parts in position and in resisting relative rotary movement between the element E and the screw 22. If desired, also, a thin coating of thin cement may be applied to the interengaged threaded portions of the mounting portion 16 and the chamber C, particularly if the mounting portion 16 is made of a material that does not lend itself to the formation therein or thereon of accurate threads to match the accuracy of the threads with which the walls of the chamber C may be provided—as by tapping. In such case the cement serves not only as a dependable joining or securing medium, but also, in filling the spaces left by any irregularities in the otherwise mating threaded portions, gives the mounting more dependably the advantages of strength, rigidity, and security of a tightly interfitted threaded joint.

Replacement of the elements E in Fig. 3 is greatly facilitated. If a cement is employed, the cemented joints may be initially weakened or broken by an initial slight turning movement applied to the screw 22 to apply upward stress (as viewed in Fig. 3) to the securing portion 16, thus straining the cement of the joint and weakening it sufficiently or breaking it, so that, after then backing the screw 22 out of the hole 21, a tool may be applied to the element E to unthread it. If no cement is employed, the locking screw is simply backed off and out of the threaded hole 21, and thereafter the element E unthreaded from the chamber C.

Referring now to Fig. 4, I construct the anti-

lever mounting portion 16 of the abrasive element E so that it may function when seated in the chamber C as one of two clamping elements which, in coaction with a suitable connecting tension element, can serve to clamp between them a suitable portion of the annular support 10. Thus I provide a tension member 31, for example, of round cross-section and of steel, to pass freely through the threaded hole 21 with which its unthreaded shank preferably snugly interfits, and provide it at one end with a head 32 to serve as the other clamping element which can engage throughout a suitably large area with the annular bottom face 27a of the counterbore 27; at its other end the tension member 31 is threaded for threaded engagement with the mounting portion 16 which, in this illustrative embodiment, in effect functions as a nut. Thus the mounting portion 16 is provided with a threaded hole 16a opening at its bottom end face 23, being preferably of substantial extent or depth, preferably along the axis of the element E where the latter is of circular cross-section and where only one tension element is to be employed.

The element E, with or without cement applied to its mounting portion and to the walls of the chamber C, may thus be tightly drawn into the chamber C by operation of the companion clamping element at the other end of the tension rod 31, such as the head 32 integrally formed therewith and suitably shaped, for example, hexagonally, so that it may be engaged by a suitable tool, such as a socket wrench, and turned to cause the head 32 and the element E, through the mounting portion 16 thereof, tightly to clamp the annular support 10 therebetween. Here also, if desired, the mounting portion 16 of the element E may be pressure or force-fitted into position; in such case the headed tension member 31 may thereafter be applied and put under tension, in effect locking the anchorage against loosening up.

When replacement is necessary, the part 31—32 is unthreaded from the threaded hole 16a in the mounting portion 16, whence a screw, like the screw 22 of Fig. 2 or 3, is then threaded into the threaded hole 21 to dislodge the element E from the chamber C and, if a cement is employed, to break the union or junction effected by the cement.

Where the tension element 31 is threaded into the element E, the mounting portion 16 of the latter is preferably made of a material such as metal, resinoid, powdered metal, resin-bonded powdered metal, hard rubber, or like materials that are better adapted for the formation of threads therein and to take the strain, particularly where the element E is set in the chamber without the use of a cement or the like and the clamping action is relied upon to retain it in place. However, many of the advantages of my invention may be achieved with the use of materials less well adapted for threading and taking a substantial strain on the threads, for in such case a cement or like substance is preferably employed on the walls of the chamber C, the threaded arrangement and tension member sufficing to draw the element E dependably into position within the chamber C for subsequent setting of the cement or like securing material. Moreover, with materials less well adapted for direct interengagement threadedly with the threaded tension element 31, such as ceramically or vitrified-bonded materials, resinoid, hard rubber, and even some metals or alloys, I may embody into the mounting

portion a relatively heavy or large sleeve or bushing 34 made of any material, preferably metallic, suitable for threading to take the stresses imposed by the element 31; member 34 is internally threaded to coat with the threaded element 31 and its relatively large external surface, of substantial dimension both axially and radially, may be made irregular as indicated at 34a in any suitable way, as by coarse knurling, fluting, threading, or other variations in surface contour whereby it may be interengaged with the material of the mounting portion 16, as by moulding the latter thereabout, and thus forming an interlock that is mechanically stronger than would be a direct threaded connection of the element 31 with the mounting portion 16. Such an insert, preferably having its end face flush with the end face of the portion 16, thus also serves as an anvil against which the ejecting screw, like screw 22 of Fig. 2 or 3, is abutted to dislodge the element from the chamber C, thus distributing the force of the screw and aiding to prevent crushing or fragmentation of the mounting portion 16 during the ejecting process.

In all forms disclosed, I may also employ a slight taper, hardly distinguishable in the drawing, in the mating shapes of the chamber C and the mounting portion 16, giving a wedging self-seating or self-tightening action under the pressures of grinding, particularly in the forms of Figs. 2, 4, and 5 and to a lesser extent in the form of Fig. 3. Such taper also facilitates dislodgment under the action of the screw 22. The upper part of the mounting portion 16, exposed above the face 12 of the support 10, may be cross-sectioned to receive a suitable wrench as by providing it with opposed parallel faces 34 and 35 formed by moulding, grinding, milling, or the like; thereby an applied wrench may be used to hold the element E of Figs. 4 and 5 against turning while tightening up the tension element 31, and to turn the element E in Fig. 3 relative to the threaded walls of chamber C, and to aid in loosening up the elements E in all of the illustrative forms when it is desired to remove them from the chamber C of the support 10.

Likewise many advantages of my invention may be achieved by the use of securing media other than cements such as those above mentioned. For example, where the part of the abrasive element E that enters the chamber C and the annular support 10 are both of metal suitable to be joined together by any of various solders, solders may be employed and the parts 55 sweated together. In such case, to effect replacement, heat may be applied to weaken the metallurgical junction and the inserted element expelled or forced out of the chamber C by the means above described. In like manner such a junction may be effected as at P, in joining the abrasive portion 15 and the mounting portion 16 where metals are used that are suitable for effecting such junction.

It will thus be seen that there has been provided in this invention a disk type of grinding wheel construction in which many thoroughly practical advantages are successfully achieved. The composite elements E, comprising the diamond abrasive portion 15 and the securing portion 16, can be efficiently manufactured with the diamond abrasive portion 15 constructed to have desired abrading characteristics according to the requirements of the particular material to be ground or the particular grinding operation to be performed, whence the mounting portion 16

can, in turn, be constructed to coat with the abrasive portion in meeting the particular requirements of any particular grinding operation. For example, for some operations a hard, rigid mounting or support for the active abrasive part may be needed, and in such case the mounting portion 16 may be made of a suitably hard metal, or by powdered metallurgy, or, by way of further example, it may be a ceramically or vitrified bonded structure. For some other grinding operation the active abrading part, such as the part 15, might need a relatively less rigid or stiff support, and in such case the mounting portion 16 may be made of a material like natural or synthetic rubber suitably compounded to give the desired hardness, accompanied by such yieldability as may be desired; or other resinoids, with appropriate fillers, may be used in making the mounting portion 16 to have a lower modulus of elasticity appropriate to the particular grinding operation to be performed. Thus a wide variety of grinding requirements can be met in a thoroughly practical way and with greater economy and efficiency than has heretofore been possible. The composite abrasive elements E can be standardized dimensionally for assembly to similarly standardized annular supports 10, thus to facilitate initial making up or assembly of grinding disks of the desired grinding characteristics, and the construction facilitates the ready replacement or substitution, by the user, of the composite abrasive elements. The latter are easily removed from their chambers, even though strong cements or even tight or force fits are employed, and the assembly of new elements to the annular support 10 easily effected. In this latter connection, where cements, solders, or the like are employed, it is preferred that the lower ends of the mounting portions 16 be chamfered or rounded over, as at 20 in the drawings, thus not only facilitating entry of the mounting portion 16 into the chamber C, but also to provide an internal space for the accumulation of surplus securing material such as the cement, solder, or other material in the event that it is inadvertently applied initially somewhat in excess.

Moreover, it will be seen that the composite parts E, according to my invention, are capable of being dependably, securely, and rigidly held in position against the severe stresses and reactions caused by the grinding operation being performed, and that this advantage and other advantages I am enabled to gain without risk of straining or distorting the abrasive portion itself. Each mounting portion 16 serves in effect as a cantilever that takes the stresses from the abrasive portion 15 and in and by itself transmits them to the annular support 10 in a way to avoid direct reaction between the abrasive portion 15 and any part of the support 10. Uniformity of mounting and alignment of the abrasive faces 15a is thereby achievable and maintenance of precision of grinding operation facilitated.

I am thus enabled to bring diamond abrasive materials efficiently and inexpensively into operation for surface grinding of large areas of work-pieces such as granite, marble, plate glass, and the like; the disk grinding wheel of my invention may be economically constructed and operated in relatively large dimensions and will be seen to be well adapted to withstand the great pressures which have to be employed in such operations; of the total or aggregate pressure with which the rotating structure is pressed against the work, each mounting portion 16

transmits to its abrasive portion 15 the share of the total pressure under which the abrasive portion 15 by itself should operate upon the work-piece. With such substantial pressures, the reaction from the plane of grinding upon the exposed length of the cantilever mounting portion 16 is one to tend to displace and strain it in a direction transversely of its axis, as well as to put it under compression. The non-abrasive mounting portion 16, according to my invention, can be constructed of materials having structural characteristics uninhibited by the limitations which are imposed if the elements E had to be of the same bonded abrasive structure throughout, and hence I am enabled to make effective the diamond abrasive material in that the structures according to my invention can function under stresses of magnitude greater than heretofore possible. As another result also vastly increased grinding capacity is achieved and, aside from making substantial savings in initial cost of manufacture of diamond abrasive disks, lower cost and higher efficiency of grinding operations are achieved.

Furthermore, tendency toward chattering or like detrimental actions during grinding operations is guarded against in a reliable manner. The transverse reactions from the grinding operation are dependably resisted by the cantilever action of the cantilever portions 16 which insure unyielding support and holding of the abrasive wafers 15, aided by the dependable seating and anchorage of substantial lengths of these cantilever portions 16 in the respective chamber parts C of the annular support 10 to which such reactions are dependably transmitted and by which they are absorbed.

As many possible embodiments may be made of the above invention and as many changes might be made in the embodiment above set forth, it is to be understood that all matter hereinabove set forth or shown in the accompanying drawing is to be interpreted as illustrative and not in a limiting sense.

I claim:

1. A grinding wheel construction comprising an annular support being recessed in a back face thereof to give it substantially a U-shaped cross-section and having a plurality of chambers of substantial depth and cross-section opening into the front face thereof, said support having a hole leading from the annular recess into the chamber and through the bottom of the latter, a plurality of built-up elements, one for each chamber and each comprising a cantilever mounting portion received and secured in a chamber and carrying an abrasive portion at its outer end, and means coacting with said hole and operable to dislodge the element from its chamber.

2. A grinding wheel construction comprising a rigid annular support having opening into the front face thereof a plurality of chambers having fixed walls of substantial rigidity and giving each chamber substantial cross-section and depth, a plurality of built-up elements, one for each chamber and each comprising a cantilever mounting portion of greater length than the depth of a chamber and received within its chamber and only by the walls of the latter rigidly supported for cantilever action of the portion thereof that projects beyond said front face, said projecting portion carrying at its outer end an abrasive portion of relatively small thickness and comprising bonded diamond grains, said cantilever portion and the walls of the chamber coacting to prevent

13

material transverse deflection under the transversely directed forces accompanying grinding action by the abrasive portion, the support being recessed at the back face thereof opposite each chamber, there being a hole through the annular support from the bottom of each chamber and extending to the recessed back face, and screws extending through the holes and into the recessed back face and each screw being reachable for turning at said back face and each screw being operable to dislodge the corresponding element from its chamber when desired.

GUNNAR E. HOLLSTROM.
